INVENTOR.

Allen Arkley

BY

Harry A. Totten

ATTORNEY.

UNITED STATES PATENT OFFICE.

ALLEN ARKLEY, OF SANTA BARBARA, CALIFORNIA.

CARBURETOR.

Application filed January 3, 1927. Serial No. 158,436.

The present invention relates to improvements in carburetors, and has for its principal objects to provide a carburetor adapted for installation in any position in relation to the apparatus with which it is connected; to provide in a carburetor a fuel feed nozzle having associated therewith a throttle longitudinally movable relative thereto to control the fuel discharge into the carburetor chamber; to provide a carburetor structure wherein there is incorporated a venturi movable to and from the throttle valve controlling the entrance of air into the carburetor for mixing with the fuel discharge; to provide a structure wherein in the air admitted into the mixing chamber is throughout the entire circumferential area of the chamber ensuring a uniform mixture and carburetion; to provide operating means for the throttle valve and venturi whereby the same may be simultaneously operated linearly of the chamber to and from each other, and wherein the throttle valve in its movement actuates the movement of the venturi.

Other objects are to provide a carburetor choke control, the operation of which affords a major control from the main air inlet port to the mixing chamber. Other objects will be apparent from the following description.

The invention consists primarily in a force feed carburetor wherein the fuel is discharged into the mixing chamber in a jet stream under pressure, and wherein the linear movement of the throttle valve relative to the discharge nozzle increases or diminishes the fuel discharge into the mixing chamber, and wherein the movement of the venturi constituting the mixing chamber automatically regulates the supply of air for carburetion dependent on the position of the throttle valve relatively to the nozzle valve.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may

be resorted to without departing from the spirit or sacrificing any of the advantages of the invention.

To more fully comprehend the invention, reference is directed to the accompanying drawings, wherein

Fig. 1 is a view in elevation of the preferred embodiment of my invention.

Fig. 2 is a similar view taken at right angles to the illustration shown in Fig. 1.

Fig. 3 is a view in top plan.

Fig. 4 is a vertical central sectional view on line 4—4, of Fig. 3.

Fig. 5 is a transverse sectional view taken on line 5—5 of Figs. 1 and 4.

Fig. 6 is a transverse sectional view taken on line 6—6 of Fig. 2, and

Fig. 7 is a transverse sectional view taken on line 7—7 of Figs. 2 and 4.

Referring more particularly to the drawings wherein like characters of reference designate corresponding parts, 1 indicates a tubular carburetor shell mounting at one end an attaching plate 2 preferably threaded thereon as at 3 for securing the discharge end of the carburetor shell to a motor or the like. The opposite end of the shell is adapted to be closed by a plate 4 attached thereto in any suitable manner by screws 5. The plate carries on its inner face a tubular nozzle 6 disposed concentrically of the shell 1, and tapered at its end at 7 in needle formation. The fuel feed bore 8 of the nozzle opens through lateral ports 9 at its needle end 7, and at its opposite end is adapted to communicate through a connection or elbow 10 with a suitable pressure fuel feed device 11, that embodiment illustrated representing what is commonly termed the "auto pulse magnetic fuel pump", the construction and formation of which forms no part of the present invention.

While this form of fuel feed device is illustrated, it is to be understood that any mechanism capable of supplying fuel under pressure to the bore 8 may be employed.

Air is admitted into the carburetor shell 1 at a point adjacent to the discharge end of the nozzle 6 through an annular series of vertical ports 12 formed in the surface of the shell 1. The area of these ports is adapted to be controlled by a cylinder valve

13 surrounding the carburetor shell 1, said valve being provided circumferentially with a plurality of air inlet ports 14 of a size corresponding to the ports 12.

- 14 Any suitable mechanism may be employed for rotating the valve 13 about the shell 1. Slidably mounted within the carburetor shell 1 with its periphery in frictional contact with the inner surface of the shell wall 15 is a Venturi tube 15, and upwardly from said Venturi tube 15 extends a stem 16, the upper end of which bears against a cam surface 17, the present embodiment being illustrated as formed on the inner face of the member 4. To the lower end of the nozzle 6 is threaded a throttle valve 18, the periphery of which has frictional contact with the inner wall surface of the shell 1, and said throttle valve through said threaded connection is adapted for axial rotation about the nozzle 6 with the needle end 7 of the nozzle adapted to project through an outlet orifice 19 disposed concentrically of the lower conical end 20 of the throttle valve.
- 15 The end of the outlet orifice 19 has removably positioned therein a ported plate 21 which controls the effective discharge area of the orifice 19 through which fuel passing from the ports 9 and entering the orifice 19 is discharged from the latter into the mixing chamber formed by the venturi 15. The throttle valve 18 is provided with a bore 22 extending longitudinally therethrough, and in which is slidably received the stem 16, a spring 23 surrounding the stem and bearing on the end of the throttle valve 18, and held under compression by a member 24 illustrated in the form of a cotter pin, maintains the upper end of the stem 16 in contact with the cam surface 17. Axial rotation is imparted to the throttle valve 18 by operation of the throttle valve operating collar 25, connected with the throttle valve by a screw member 26, which extends through and operates in a slot 27 formed in the wall surface of the shell 1 above the ports 12, as illustrated in Figs. 4 and 5. An auxiliary air opening or inlet, commonly termed the low speed air supply, is admitted into the shell 1 at a point preferably below the end of the venturi 15 through an air inlet opening 28, which is conventionally illustrated in the drawings.

16 Any mechanism for axially rotating the members 13 and 25 on the carburetor shell 1 is not deemed necessary to be illustrated, as any suitable form of mechanism may be employed.

- 17 With fuel supplied under pressure into the bore 8 of the nozzle 6, it will be observed that with the throttle valve 18 axially rotated on the nozzle 6 to seat its interior end in the opening in member 21, the entrance of fuel into the venturi 15 will be precluded. 18 In this position of the throttle valve, the

upper edge of the Venturi tube will circumferentially seat on the periphery of the conical end of the valve 18. When it is desired to admit fuel into the mixing chamber formed by the venturi 15, the same is accomplished by rotating the collar 25 to linearly move the throttle valve 18 toward the discharge end of the nozzle 6. This movement will regulate the operating area of the fuel discharge around the needle end 7 of the member 6 and at the same time will cause a separation or unseating between the adjacent ends of the throttle valve 18 and venturi 15, admitting a supply of air circumferentially of the fuel supply, discharging axially into the Venturi tube 15. This movement increases or decreases automatically in accordance with the movement of the throttle valve 18 linearly of the nozzle 6 to increase or decrease the fuel flow from the port 19 in the member 21. The maximum quantity of air admissible through the ports 12 may be varied by adjusting the member 13 to vary the effective area of said ports.

19 I claim:—

20 1. A carburetor including a chambered body formed with an air inlet port and a mixture discharge, a fuel feed nozzle discharging into the body chamber, a linearly movable throttle valve associated with the nozzle for controlling the fuel discharge therefrom, a linearly movable Venturi tube associated with the end of said throttle valve and within which said valve is adapted for circumferential seating; means for axially rotating said valve, a connection between said valve and Venturi tube whereby axial rotation is imparted to the latter, and a cam for acting on the Venturi tube during its axial rotation to move the same relatively to said valve.

21 2. A carburetor including a chambered body formed with an air inlet port and a mixture discharge, a fuel feed nozzle extending axially into the body chamber and discharging thereinto at a point opposite the air inlet port, a throttle valve provided with a central bore into and through which said nozzle is adapted to extend, a threaded connection between said throttle valve and nozzle, said throttle valve provided with a conical end, a Venturi tube linearly movable within said body chamber and within which said conical valve end is adapted for circumferential seating, a stem extended from said Venturi tube and passing through a guide opening in said valve, a spring for normally drawing said Venturi tube toward the conical end of said valve, a cam coaxial with the end of said stem, and a ring surrounding said body and having operating connection with said valve whereby the same is caused to rotate about said stem.

22 3. A carburetor including a chambered body formed with an air inlet port and a

mixture discharge, a fuel feed nozzle discharging into the body chamber, a linearly movable throttle valve associated with the nozzle for controlling the fuel discharge circumferential seating; and means for simultaneously moving said Venturi tube and throttle valve in relatively opposite directions. 10

5 therefrom, a linearly movable Venturi tube associated with the end of said throttle valve and within which said valve is adapted for

In testimony whereof I have signed my name to this specification.

ALLEN ARKLEY.
